(No Model.)

J. PETTERSON & L. H. LIEBECK.
WATER STILL.

No. 478,458.

Patented July 5, 1892.

UNITED STATES PATENT OFFICE.

JOHANNES PETTERSON AND LOUIS H. LIEBECK, OF NEW YORK, N. Y.

WATER-STILL.

SPECIFICATION forming part of Letters Patent No. 478,458, dated July 5, 1892.

Application filed March 11, 1892. Serial No. 424,553. (No model.)

To all whom it may concern:

Be it known that we, JOHANNES PETTERSON and LOUIS H. LIEBECK, of the city, county, and State of New York, have invented a new 5 and Improved Water-Still, of which the following is a full, clear, and exact description.

Our invention relates to improvements in water-stills and condensing apparatus; and its object is to produce a simple apparatus by 10 means of which a large and continuous supply of water may be distilled and rendered absolutely pure, so as to adapt it for either drinking or medicinal purposes.

To this end our invention consists of certain 15 features of construction and combinations of parts, which will be hereinafter described and claimed.

Reference is to be had to the accompanying drawing, forming a part of this specification, 20 in which the figure is a detail sectional elevation of the entire apparatus.

The apparatus is provided with a receiving and cooling tank 10, which may be held on any convenient support, such as 11, and which 25 has an inlet-pipe 12 near the bottom, the pipe being controlled by a cock and adapted to connect with any suitable source of water-supply. Opening from the tank near the top is a discharge-pipe 13, which leads to the lower 30 portion 14 of a filter 15, and the filter comprises an open-topped case in which is held near the bottom a filtering-bed 16, this being preferably of powdered glass, which is contained between two parallel and horizontal 35 perforated plates 17.

At one end of the filter is a swinging elbow-pipe 15^a, which opens from the middle portion of the filter, and when turned up, as indicated by dotted lines in the drawing, the 40 open end of the pipe will extend to a point opposite the top of the filter, and when turned down it will be beneath the filter-top, as shown in the drawing, and the water may run freely through it. The object of the pipe is to facilitate the starting and cleaning of the filter. The short leg of the elbow-pipe is closed, and consequently when the pipe is turned up the filter 15 will fill with water, thus bringing the water-level above the bend 20 in the pipe 19, 45 so that the water will flow freely through; but after it is once started the water will have a siphon action and will continue to flow, and

the pipe 15^a may be turned down, so that the scum which has risen with the high water in the filter may flow off through it into any 55 suitable receptacle which may be arranged to receive it. After the water has started through the pipe 19 it will continue to flow through the same and will not reach the level of the outlet-pipe 15^a.

The filter is provided with a hopper-like bottom, from the middle portion of which opens a cock-controlled vent-pipe 18, by means of which the filter may be cleaned. A discharge-pipe 19 opens from the filter-case above the bed 60 16, the pipe having an upward bend 20 therein, which extends to a point about level with the top of the filter, and consequently the water will necessarily rise to the top of the filter before it flows through the pipe 19, and only clear 65 water will be allowed to flow through the pipe. The pipe 19 extends into the steam-dome 21 of a boiler 22 and is formed into a coil 23 in the upper portion of the dome, and this coil serves as a feed-water heater. After leaving 70 the coil 23 the pipe emerges at the side of the dome, as shown at 24, extends downward to a point adjacent to the bottom of the dome, and is then bent upward and arranged to deliver, as shown at 25, within the dome and 75 near the center of the same. The boiler 22 may be of any approved shape, but it is preferably cylindrical, and the steam-dome 21 is fastened securely in the upper part of the same.

Within the steam-dome and beneath the inlet 25 is a series of annular and convex plates 26, which are arranged one above the other and which have short vertical annular flanges or pipes near the middle, the flange or pipe 90 27^a of the upper plate being elongated to extend upward to a similar series of plates in the upper portion of the dome, the plates being arranged, as shown in the drawing, in groups in the upper and lower portions of the 95 steam-dome. The plates 26 are of less diameter than the steam-dome and they deliver upon concave plates 28, which are secured to the sides of the dome and have central apertures which encircle the short pipes or flanges 100 27 of the plates 26. The water within will flow downward and outward over the plates 26, inward over the plates 28, and will finally be delivered to the lower portion of the boiler,

while the steam generated in the boiler may rise freely through the central apertures in the several plates and pass out through the pipe at the top of the dome. This arrangement of the plates causes the water to be spread over considerable surface and quickly heated.

The boiler is provided near its lower portion—that is, below the center—with try-cocks 29 and 30, and in the bottom of the boiler is a steam-coil 31, by means of which the water is heated, the coil having the cock-controlled inlet 32 and a suitable outlet 33. The boiler has a discharge-pipe 34 opening from its lower portion, this being controlled by a cock 35, and a pipe 36 extends vertically upward between the cock 35 and the boiler, the pipe 36 terminating at its upper end in a glass case 37, which has a vent-pipe 38 opening into the air and a discharge-pipe 39 leading back to the pipe 34. The case 37 is at about the proper level of water in the boiler, and by means of it the height of the water may be observed.

25 Opening from the top of the steam-dome 21 is a steam-pipe 40, which delivers into a steam-filter comprising a tight-casing 41 and a plurality of vertical filtering-beds 42, formed of powdered glass and held between perforated plates 43. The filter-case has a hook 44 within it to facilitate its handling, and opening from the bottom of the filter are pipes 44^a and 45, which extend downward into the water-filter and deliver, respectively, above and below the filter-bed 16 thereof. This construction enables any of the condensed steam in the steam-filter to escape into the water-filter, so that only the pure white steam will pass through the steam-filter and into the discharge-pipe 46, which opens therefrom. This pipe 46 delivers into a condensing-cylinder 47, which is held longitudinally within the cooling-tank 10. The cylinder 47 has a large central bore 48, which is open at the bottom, and the water-containing surface of the cylinder is thus reduced to a thin annular chamber 49, so that the steam which enters the cylinder will be exposed to a large cooling-surface both without and within and will be 50 quickly condensed.

Within the water-holding chamber 49 is a coil of small pipe 50, which is adapted to contain cold water to hasten condensation, this coil having a cock-controlled inlet 51 at the bottom and a discharge 52 at the top, the coil discharging into the upper portion of the tank 10. The cylinder 47 has at the bottom a discharge-pipe 53, which has a vertical pipe 54 connecting with the air and which is bent 55 downward and then upward to connect with

a chamber 55, the depending bend in the pipe having a cock-controlled vent 56. The chamber 55 has a cock-controlled vent 57 and a discharge-pipe 58, which leads to a suitable receiving-vessel 59. The discharge-pipe 58 is 65 also connected with the air by a vertical pipe 60, which facilitates a rapid flow of water.

It will be seen by the foregoing description that a continuous circulation of water may be maintained, the water entering at the inlet 12, passing through the tank 10, and from thence through the water-filter 15, and from thence through the heating-coil and into the boiler. The water is rapidly converted into steam and the steam is filtered and condensed, 75 and finally issues in the form of pure water through the pipes 53 and 58 into the receiver 59.

Having thus fully described our invention, we claim as new and desire to secure by Letters Patent—

1. An apparatus of the character described, comprising a water-tank connected with a source of water-supply, a filter connected with the tank, a boiler having a steam-dome 85 therein and having a pipe connection with the filter, a steam-filter connected with the steam-dome, and a cooling-cylinder held within the tank, the cylinder having its upper end connected with the steam-filter and its lower end provided with a discharge-pipe, substantially as described.

2. An apparatus of the character described, comprising a water-tank having a suitable inlet, a water-filter connected with the tank, a 95 steam-boiler having a steam-dome therein, a pipe leading from the filter through and into the steam-dome, the pipe being formed into a coil within the dome, a steam-filter connected with the steam-dome, a water-cooling 100 cylinder held within the tank and connected with the steam-filter, and a discharge-pipe opening from the cooling-cylinder, substantially as described.

3. The combination, with the water-receptacle 10, of the cooling-cylinder 47 arranged therein, the cylinder having a central bore open at one end and closed at the other, an inlet-pipe opening into one end of the cylinder, an outlet-pipe opening from the opposite end of the cylinder, and a cooling-coil held within the chamber which surrounds the bore of the cylinder, the coil having a suitable inlet and outlet, substantially as described.
